UNITED STATES PATENT OFFICE.

GEORGE COOK, OF ALLENDALE, NEW JERSEY, ASSIGNOR TO AMERICAN BRAKE SHOE & FOUNDRY COMPANY, OF MAHWAH, NEW JERSEY, A CORPORATION OF NEW JERSEY.

REINFORCED LUG FOR BRAKE-SHOES.

1,109,112.

Specification of Letters Patent. Patented Sept. 1, 1914.

Application filed May 23, 1913. Serial No. 769,373.

To all whom it may concern:

Be it known that I, GEORGE COOK, a citizen of the United States, and a resident of Allendale, in the county of Bergen and State of New Jersey, have made and invented certain new and useful Improvements in Reinforced Lugs for Brake-Shoes, of which the following is a specification.

My invention relates to an improvement in backs for brake shoes, and more particularly to that kind or type thereof employing a wrought metal key lug for securing the shoe to the brake head. In shoes using a reinforcing back, the attaching or key lug has been made of a separate piece or strap of wrought metal, the ends of the lug being bent or tucked under the back for the purpose of securely anchoring it in place. In practice, it has been found that this construction of lug has certain disadvantages, more particularly because of the fact that the edges of the lug injure, and in some instances entirely destroy, the feet of the brake head against which they impinge, there being more or less play between the brake shoe and head. In order to overcome this objection, the wrought metal lug is sometimes reinforced by the cast metal forming the body of the shoe, a wider or broader surface being thereby presented to the depending feet of the brake head. This cast metal, however, being brittle, is apt to be cracked and broken away when the shoe is in service and also during handling or transportation, the wrought metal lug being thus naked to injure the brake head as above described.

The object of my invention is to reinforce the key lug of the shoe by the metal of the lug itself, or by the metal of the steel back, the surface of the key lug presented to the lugs or feet on the brake head being of sufficient width to prevent cutting or injuring the latter, and also overcoming any and all liability of becoming cracked or broken away as in the case of the cast metal reinforce.

With this and other ends in view, the invention consists in certain novel features of construction and combinations of parts as will be hereinafter fully described and pointed out in the claims.

In the accompanying drawings, Figure 1 is a view in perspective of a steel back slit and bent to reinforce a key lug, in ac-

cordance with my invention. Fig. 2 is a view in cross-section of a brake shoe showing the key lug applied thereto and reinforced with the metal forming the steel back. Fig. 3 is a view in perspective of a modified form of the back, and Fig. 4 a view in cross-section of a brake shoe having applied thereto the back illustrated in Fig. 3 and with the key lug assembled therewith. Figs. 5 and 6 are views in cross-section of brake shoes illustrating the strap lug having its vertical walls formed of several thicknesses of metal and reinforced by the metal of the steel back. Figs. 7 and 8 are views in perspective of parts of a steel back formed like those illustrated in Figs. 1 and 3 but with the central portion of the back bent or stamped upwardly. Fig. 9 is a sectional view of a modification somewhat similar to that shown in Fig. 6, but with the upper portion of the lug reinforced.

Referring to the drawings, I may accomplish the object of my invention by constructing the back 20 as illustrated in Fig. 1, the same being formed of steel or wrought metal, and preferably provided with the openings 21 through which the molten cast metal of the body may flow to assist in anchoring the back at or adjacent to the rear surface of the body 22 of the shoe, Fig. 2. About midway its length, the back is slotted inwardly from each edge, the reinforcing pieces or plates 23 being struck upwardly at approximately right angles to the back 20, forming recesses 24, the height of said reinforcing plates 23 being substantially that of the attaching lug, Fig. 2. This attaching lug is made in the form of a strap and bent to form vertical sides 25, and a top plate 26, the sides 25 fitting in the recesses 24 and having their extreme ends 27 bent under and below the central portion 27^a of the back 20 lying between the plates 23, to thereby securely engage the lug with the back and prevent the same from becoming disengaged from the body of the shoe 22.

In order to prevent the ends of the lug from extending too deeply into the body of the shoe, that portion of the back illustrated at 27^a, Fig. 1, may be struck or bent upwardly as illustrated at 27^b, Fig. 7, and again instead of having the back of one continuous curve as illustrated in Fig. 3, the central portion thereof may be struck or bent upwardly as illustrated at 27^c, Fig. 8,

this form of back permitting the ends of the strap lug to be bent and anchored under the central portion of the back and without extending too deeply into the body of the shoe 5 where portions of the lugs might be worn away in service with said body.

As illustrated in Figs. 3 and 4, instead of slitting the back from the outer edges inwardly, it may be so slitted as to form an 10 opening 28 about midway the length of the back 29, the metal between the slits being bent upwardly at substantially right angles to said back 29 to form the reinforcing plates 30. In this instance, the attaching 15 lug 31, Fig. 4, will be passed down through the opening 28, and the extreme ends 32 of the sides 33 bent outwardly and under the back 29, thereby effecting a safe and secure lock with the back, as in the first instance 20 above described.

The width of the reinforcing plates in either of the above instances will be equal to that of the width of the vertical plates or sides of the attaching lug, in order that 25 the edges of said reinforcing plates and the edges of the vertical plates of the attaching lug will lie flush, thereby presenting to the contacting parts of the brake head (not shown) a surface much greater in area than 30 where the attaching lug is not reinforced. Should this surface, equal in area to the combined thicknesses of the attaching lug and reinforcing plates, be not sufficient, it may be still further increased by doubling 35 the vertical sides of the attaching lug upon themselves, as illustrated in Figs. 5 and 6. In Fig. 5 the vertical sides 34 are bent inwardly and under the back 35 and then upwardly to form reinforcing plates 36, the 40 said reinforcing plates 36 lying and terminating on the outer side or surface of the vertical sides 34. In Fig. 6 practically the same construction is illustrated, excepting that the vertical sides 37 of the strap lug 45 are bent inwardly under the back 38 and then upwardly between the plates or sides 37 and the reinforcing plates 39. In both instances illustrated in Figs. 5 and 6, the surface of the reinforced lug presented to 50 the contacting portions of the brake head is equal to double the thickness of the attaching lug plus the thickness of the reinforcing plates struck up from the back, a surface sufficient to avoid the cutting or injury to the brake head before alluded to.

If desired, in addition to reinforcing the vertical walls or sides of the lug, the upper portion or top plate may also be reinforced or made of two or more thicknesses. For instance, in Fig. 9 I have shown a sectional view of a key lug, constructed somewhat in the same manner as that illustrated in Fig. 6, excepting that the top plate of the lug is made of double thickness, the vertical walls 40 of the lug being continued around over 65 the tops of the reinforcing walls 41, the sides of the lug in this instance consisting of the plates 40, 41 and 42, and the top of the lug of the plates 43, 44, the side or vertical walls being of three thicknesses, and 70 the top of the lug of two thicknesses.

It will be understood from the foregoing that when the back and lug are formed and assembled as described, the attaching lug will present a sufficiently broad surface to 75 the feet or lugs of the brake head to avoid any and all danger of injury thereto. Furthermore, as both the lug and reinforcement therefor are formed of steel or wrought metal, all danger of the cracking or breaking thereof, either in service or during the loading or unloading of the shoes, or transportation thereof, is also avoided.

What I claim is:—

1. A back for a brake shoe comprising a 85 back proper, and a key lug made separate therefrom and attached thereto, the vertical walls of said key lug being folded backwardly upon themselves whereby to increase the surface of the edges thereof. 90

2. A back for a brake shoe comprising a back proper, and a key lug made separate therefrom and attached thereto, the vertical walls of said key lug being folded back upon themselves, and reinforced by the metal of 95 the back proper.

3. A back for a brake shoe having a key lug made separate therefrom and secured thereto, the vertical walls and top of said key lug being made of a plurality of layers 100 of metal, the vertical walls of said lug being reinforced by the metal of said back.

Signed at New York, borough of Manhattan, in the county of New York and State of New York, this 26th day of May, 105 A. D. 1913.

GEORGE COOK.
